(57) CLAIM

The ornamental design for a garment, as shown and described.

DESCRIPTION

FIG. 1 is a front left perspective view of a garment showing our new design;

FIG. 2 is a rear left perspective view thereof;

FIG. 3 is a left side view thereof;

FIG. 4 is a front view thereof; and,

FIG. 5 is a rear view thereof.

The broken lines immediately adjacent to the shaded area represent unclaimed boundaries of the design. The broken lines within the shaded area represent disclaimed seam and stitch lines and form no part of the claimed design. The unshaded rectangular region within the shaded area forms no part of the claimed design. The broken lines showing the remainder of the garment represent unclaimed subject matter and form no part of the claimed design.
